(57) **CLAIM**

The ornamental design for an electric ice scraper, as shown and described.

DESCRIPTION

FIG. 1 is a front, right, top perspective view of an electric ice scraper, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top of the electric ice scraper in a detached state;

FIG. 10 is a rear, left, bottom of the electric ice scraper in a detached state; and,

FIG. 11 is an enlarged view of detail 11 in FIG. 9.

The dashed broken lines in the figures illustrate portions of the electric ice scraper that form no part of the claimed design.

The dash-dot-dash broken lines are for notating enlarged views and form no part of the claimed design.
